UNITED STATES PATENT OFFICE.

WILLIAM C. BANKS, OF COMO, MISSISSIPPI, ASSIGNOR TO REBECCA BANKS,
OF SAME PLACE.

IMPROVEMENT IN FARM-FENCES.

Specification forming part of Letters Patent No. **155,915**, dated October 13, 1874; application filed
July 23, 1874.

To all whom it may concern:

Be it known that I, WILLIAM C. BANKS, of
Como, in the county of Panola and State of
Mississippi, have invented a new and Improved
Fence; and I do hereby declare that the fol-
lowing is a full, clear, and exact description
of the same, reference being had to the accom-
panying drawings, forming a part of this speci-
fication, in which—

Figure 1 is a side elevation; Fig. 2, a plan
view; Fig. 3, a vertical cross-section.

The invention relates to modes of construct-
ing fences for farms and plantations so that
they may be cheap and durable.

The invention will first be fully described,
and then pointed out in the claim.

A represents a series of rails, B B the
crossed supporting pair of stakes, and C the
riders. D is a short post, which may be driven
into the ground with a maul or other instru-
ment, and supports on each side the ends

of a different panel of rails. The latter rest upon
blocks E, preferably placed alternately upon op-
posite sides of the post. The bottom rails are
first laid upon blocks E, so that their ends
will abut upon different sides of two adjacent
posts, D D. On these are again placed blocks
upon which a rail rests. This is continued to
any desired height, when the stakes B B are ap-
plied to support the riders. By means of the
short posts D, which may be made of any con-
venient material, the fence is entirely pro-
tected against winds, floods, or storms.

Having thus described my invention, what
I claim as new is—

A fence, consisting of rails A, stakes B,
posts D, and blocks E, arranged in the man-
ner described.

WM. C. BANKS.
